UNITED STATES PATENT OFFICE.

HENNING W. PRENTIS, OF ST. LOUIS, MISSOURI.

EXHIBIT OR FILE CABINET.

SPECIFICATION forming part of Letters Patent No. 506,073, dated October 3, 1893.

Application filed July 7, 1892. Serial No. 439,207. (No model.)

To all whom it may concern:

Be it known that I, HENNING W. PRENTIS, of the city of St. Louis, and State of Missouri, have invented certain new and useful Improvements in Exhibit or File Cabinets, of which the following is a full, clear, and exact description, reference being had to the accompanying drawings, forming a part hereof.

My invention relates to an improved exhibit and file cabinet, and consists in the novel combination and construction of parts hereinafter set forth and claimed.

In the drawings, Figure 1 is a perspective-view of my invention, with the front cover removed, and several of the detachable swinging-wings in position for exhibition. Fig. 2 is a sectional plan-view, taken on line α α of Fig. 1. Fig. 3 is a detail view of a portion of the cabinet, illustrating the arrangement of a hinged stop-bar, made use of in carrying out the invention. Fig. 4 is a sectional detail-elevation, showing a portion of one wing, and illustrating the construction of the hinging-devices. Fig. 5 is a similar view, in perspective. Fig. 6 is a detail-view, in perspective, of a modified form of hinge-support. Fig. 7 is a front elevation of the cabinet shown in Fig. 1, with the front cover in position. Fig. 8 is a sectional plan-view, of a modified construction. Fig. 9 is a detail view, in perspective, of a further modified hinge-support. Fig. 10 is a detail view, in perspective, with parts broken away, illustrating a further modification in the hinge-supports for the detachable swinging-wings. Fig. 11 is a detail view of a further modification.

My invention resides, especially, in a closed protecting-chamber in which are mounted in superposed relation a series of detachable swinging-wings, adapted to be swung out of said closed protecting-chamber during examination and exhibition, and swung back within the same and concealed from view, after such examination and exhibition. By such construction there may be filed and exhibited, particularly in such places as large international-fairs, where ground, floor, and wall-space is very limited, charts, maps, pictures, drawings, school-work of all kinds from kindergarten to university, architect's - plans, photographs, engravings, wall - papers, rib-

bons, laces, silk, dry-goods samples, light hardware-samples, curtain-goods upholstery, &c. It is very useful and convenient in permanently exhibiting scientific-collections in botany, biology, entomology, &c.

1 indicates the normally-closed chamber, having top, bottom, back, sides and a removable front cover 2, which cover is secured in position by means of suitable fastenings, such as hooks 3 and lock 4, so as to be capable of prompt removal, to expose the detachable swinging-wings 5 for examination and exhibition, in the manner hereinafter described. 6 indicates upper and lower hinge-supports, located within said chamber 1 diagonally thereof, preferably, and extending therein parallel to each other a sufficient distance to support a proper number of the swinging-wings 5.

I will first describe my preferred construction, and afterward the modifications, referring particularly to Figs. 1, 2 and 3. The supports 6 may be of wood or metal, and have their ends beveled and provided with perforations 7 through which screws or nails may be passed, to secure them to the side and back, respectively, of the chamber 1. The hinge-supports 6 are provided with a series of vertical perforations, or depressions, separated a suitable distance from each other to permit the proper swinging-movement of the swinging-frames or wings, hereinafter mentioned. These perforations or apertures are indicated by the numeral 8, and form a portion of the hinge by means of which the swinging-wings are detachably supported in position. 9 indicates a series of vertical-depressions formed in each of said hinge-supports intermediate of the perforations or depressions 8, which vertical depressions are engaged by the inner edges of the wings when swung outward to the limit of their outward-movement. Such vertical depressions permit such action to occur, as will be hereinafter referred to. The swinging-wings 5 are preferably constructed in the form of light, wooden, skeleton frames having top, bottom, side, and vertical and horizontal cross-bars, to which the exhibits, before-mentioned, are secured by means of tacks, or other suitable fastening-devices. (See Fig. 1.) In the present instance, I have shown a series of school-

drawings secured to the swinging-wings by means of mucilage. The wings 5 may be hinged to the supports 6 in any manner, but L-shaped screw-hooks 10 are preferably used for such purpose—two being located upon the inner edge of each wing, with their threaded ends screwed into such edge, and with their free ends extending downward in the same direction, and in alignment, and located with respect to the inner edges of the wings 5 in respective aligned perforations 8 in upper and lower hinge-supports 6. As shown, the inner edges of the wings 5 are located and held some distance from the hinge-supports, or rather from the apertures thereof, in which construction permits movement of said wings freely in either direction. By the above construction a series of exhibit and file wings are detachably swung within a protecting-cabinet, so as to normally rest therein with their respective edges in a diagonal-line relative to the front, or back, of the cabinet, whereby the free edges of said wings are made quickly accessible to the fingers of the observer, and said wings may be consecutively swung out of said cabinet without disturbing the remaining ones, and assume a position at right-angles to the front of the cabinet with both sides exposed to view. (See Figs. 1 and 2.) 11 indicates a space in the cabinet at the free edges of the wings, in which the fingers of the observer may have free play in selecting any one, or a series, of said wings for examination. This space is a very important element of my invention. The wings are detachable from the hinge-supports, there being a space 12 provided in the cabinet between the upper edges of said wings and the top of said cabinet, and into which the said upper edges may readily be moved, by sliding the hooks 10 out of engagement with the apertures in the hinge-supports, and any one or all of the series of wings may be removed from the cabinet, for mounting exhibits upon it, or for other purposes, and afterward quickly replaced. In some instances, where heavy hardware samples, or the like, are to be exhibited, I provide separate rolling-supports for the free edges of the wings 5, by securing a suitable roller 13 to said edges in such position as to engage the inner-surface of the bottom of the cabinet, or other supporting-surface, when said wings are in their normal position at the limit of their inward movement, or when they approach the same. (See Fig. 1.) In other instances I locate upon the free edges, or some other portion, of the wings 5 a suitable knob or handle 14, for convenience in locating and identifying any one of the series, and for convenience in swinging it outward. For purposes of identification, I may number the series of wings serially, as shown in Fig. 1, or I may otherwise mark them, say alphabetically, for identification. Or, the knobs or handles 14 may be differently-shaped on each wing, or otherwise marked, for identification. The chamber, or cabinet 1, is provided with accessible-handles 15, for

convenience in moving the same about—it usually being of convenient size for such operation.

In Fig. 8 I have illustrated a modification of the device, in which the wings 5 are mounted in a series upon a simple straight-surface, which may be the wall of a building, or a portable board or strip, and it is clearly-evident that this board or strip may be the back of a cabinet, or attached thereto, and in such instance the series of wings would be mounted upon upper and lower hinge-supports 6 extending parallel with each other, and parallel with the front of the cabinet. Or, the construction shown in this figure may be used without any protecting-chamber, forming a very cheap construction: but open to the objection of not affording protection to the exhibits against dirt, dust, &c.

In Fig. 10 I have illustrated a further modification, in which the hinge-supports 6 are united by vertical bars 16, so as to form a rectangular skeleton-frame. This frame is hinged at its outer edge, by means of hinges 17, to the outer edge of the chamber or cabinet 1, so as to extend therein diagonally to its front and back, and be swung bodily, with the hinged-wings which it carries, out of said chamber or cabinet, during examination or exhibition, and moved to normal position within said chamber or cabinet after examination or exhibit of said wings carried thereby. This latter construction has its advantages, among which may be mentioned rapid access to the inner ones of the series of wings carried by said hinged-frame, for the reason that when said frame is swung outward all the series of wings are carried with it. It may be pointed out that the cabinet, or chamber, containing the swinging-wings, may be turned upon edge, so that said wings will be mounted to open downward or upward: or, said cabinet may be placed upon its back.

From the above it will be understood that the series of wings may be mounted to open in different directions, without changing their construction, and for such reason I do not limit myself to any particular position in which the hinge-supports may be located.

For the purpose of locking the wings against accidental removal, and against removal by unauthorized persons, I provide a stop-bar 18, which is located in the space 12, directly over the upper edges of all of the series of swinging-wings 5, and has a vertical thickness greater than the length of the downwardly-extending arms of the hooks 10 carried by any of the series of wings. This stop-bar, is pivotally-secured to the top of the cabinet, or to some adjacent portion of the same, so that its inner end may be swung outwardly, as shown in Fig. 10, out of the path of all of said wings during the operation of detaching them, and be swung back to normal position in said path after one or more of the wings have been replaced. The normal position of said stop-bar is shown in dotted lines in

Fig. 10. The perforations or depressions in the hinge-supports 6 are placed at determinate and relative distances apart, depending upon the thickness of the material of which the swinging-wings are composed, and depending upon the thickness of the samples or exhibits to be mounted on them. When the wings are swung outwardly, in the construction shown in Figs. 1 and 2, the corners of the inner-edges of same will swing into corresponding vertical depressions 9, located as before stated, intermediate of said perforations 8. This will permit the wings to swing a considerable distance farther than they could were not these vertical depressions so constructed, as without them the said corners of said wings would contact with the smooth outer-face of the hinge-supports and be limited in movement thereby. 20 indicates a separating-projection, or knob, which is located upon one face of each of the wings 5, so as to project a distance therefrom and be contacted by the adjacent face of the next-adjacent wing of the series, and hold it a distance from the one carrying the projection, thereby preventing rubbing of drawings or other exhibited material.

In Fig. 11 I illustrate a further modification of the hinge-support 6, and the manner of hinging the wings thereto. In said figure the hinge-support is constructed devoid of apertures in which a portion of the hinge moves, and in lieu thereof vertical pins 21 are mounted in apertures in said support so that their upper ends will be free and project above the upper surface of the support. To engage these pins I locate plates 22 having a projecting-end provided with a perforation, upon the wings 5 in the relative position occupied by the screw-hooks before-mentioned, and cause the perforations in said plates 22 to engage the said pins, as shown, and thereby form a very simple and durable hinge, capable of the functions of the said screw-hooks. Or, in still further cases, I may substitute ordinary screw-eyes 23 for the plates 22, causing the eyes thereof to engage the pins 21 carried by the hinge-support.

What I claim is—

50 1. An exhibit cabinet having horizontally-disposed hinge supports located therein and provided with vertical depressions 9, and vertically detachable frames or wings hinged to

said supports intermediate said depressions, and an adjustable bar normally located between the upper edges of said frames and the top of the cabinet; substantially as set forth. 55

2. An exhibit cabinet having horizontally-disposed hinge supports located therein and provided with pins 21, swinging frames or wings provided with hinge-plates 22, the latter being secured at one end to said frames and having their free ends turned at right angles to said secured ends and provided with apertures adapted to receive said pins, 60 and a bar pivoted at one end and adapted to be normally located between the upper edges of said frames and the top of the cabinet; substantially as set forth. 65

3. An exhibit cabinet having hinge-supports located therein and provided with a series of vertical apertures 8 separated a determinate distance from each other, provided with a series of vertical depressions 9 located intermediate of said apertures, and supporting-wings mounted upon said supports with hooks engaging the vertical apertures, substantially as set forth. 70 75

4. An exhibit cabinet having hinge supports provided with a series of vertical depressions 9, and frames or wings hinged to said supports at points intermediate said depressions; substantially as and for the purpose set forth. 80

5. In an exhibit and file cabinet, the combination, with the cabinet proper, and a series of swinging wings, of a supporting device for said wings hinged at one side the cabinet and normally occupying an oblique position within the latter; substantially as 85 and for the purpose set forth. 90

6. In an exhibit cabinet, the combination, with hinge-supports provided with pins 21, and swinging frames or wings, or hinge-plates 22 twisted to bring its ends at right angles to 95 each other, said ends being respectively provided with securing apertures and a bearing eye for receiving the pins 21; substantially as and for the purpose set forth.

In testimony whereof I affix my signature in presence of two witnesses.

HENNING W. PRENTIS.
